(57) **CLAIM**

The ornamental design for a full moon cabinet pull, as shown and described.

DESCRIPTION

FIG. 1 is a perspective view of a full moon cabinet pull;
FIG. 2 is a front elevational view thereof;
FIG. 3 is a rear elevational view thereof;
FIG. 4 is a left side view thereof;
FIG. 5 is a right side view thereof;
FIG. 6 is a top plan view thereof;
FIG. 7 is a bottom plan view thereof;
FIG. 8 is a perspective view thereof; and,
FIG. 9 is a perspective view thereof as installed in a door,
drawer, or similar structure.
The broken line showings of a door in FIG. 8 and two doors in
FIG. 9 are included for the purpose of showing environmental
structure and form no part of the claimed design.
